CLAIM

I claim the ornamental design for a camera, as shown and described.

DESCRIPTION

This application relates to four other design patent applications, all titled “Camera,” filed concurrently herewith by the Applicant Seek Thermal, Inc.

FIG. 1 is a perspective view of a camera showing the new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The dash-dash broken lines depict the portions of a camera which form no part of the claimed design.

The dot-dash broken lines represent boundaries and form no part of the claimed design.
